TAMPING MACHINE

Joseph Stuart, II, Wilmington, Del., assignor to
 Hercules Powder Company, Wilmington, Del.,
 a corporation of Delaware

Application January 23, 1947, Serial No. 723,833

8 Claims. (Cl. 86—20)

1

This invention relates to an improved tamping machine, and more particularly, to a reciprocating hydraulic tamping machine for filling and packing cartridges with dynamite or other explosive materials.

In the packaging of dynamite, particularly in the packaging or filling of large diameter cartridges with dynamite, difficulty has heretofore been encountered in obtaining a uniformly packed product of a density readily controllable over a wide range. It is desirable that successive dynamite cartridges be of uniform density in order that the explosive effect of these cartridges may be depended upon to be consistent.

The object of this invention is to provide a machine by which cartridges can be uniformly packed with explosive materials.

A further object of this invention is to provide a machine to automatically fill cartridges with an explosive material by a hydraulically actuated tamping means.

A further object of this invention is to provide a machine which will provide a uniform application of pressure to the explosive material being packed in cartridges.

A further object of this invention is to provide a machine which will produce a cartridge filled with an explosive packed to a depth and density readily controllable at the discretion of the operator.

Other objects of the invention will appear hereinafter, the novel features and combinations being set forth in the appended claims.

Generally described, this invention includes a tamping device hydraulically actuated, controls for the actuation of the tamping device, a storage member for an explosive material in alignment with the tamping device, a cartridge support assembly, and controls for the actuation of the support assembly.

A preferred embodiment of the invention has been chosen for purposes of illustration and description and is shown in the accompanying drawings forming a part of the specification, wherein Figure 1 is a partially broken front elevation of the machine; Figure 2 is an enlarged front elevational view in partial section of the adjustment control shown in Figure 1; Figure 3 is an enlarged partial section of the tamping cylinder assembly taken along line 3—3 of Figure 1; Figure 4 is a schematic diagram illustrating the hydraulic and electric systems for operating and controlling the invention. Figure 5 is a partially broken front elevation of an alternative embodiment of the invention.

2

With reference to Figure 1, 10 is the frame of the machine, the cross members of which support the tamping cylinder assembly 11 and the funnel 12. The tamping rod 13, preferably made of hard wood and secured to the piston rod 14 by suitable securing means, is reciprocated vertically by a pressured oil supply to the tamping cylinder assembly 11 through the upward pressure connection 15, tending to give upward movement to the piston rod 14 and the controlled oil pressure through the adjustable pressure connection 16 tending to give a downward movement to the piston rod 14 when the opposing force applied through the opposite pressure connection is removed.

The piston rod 14 is enlarged at its upper end forming a control block 17 to provide a means of actuating the plunger roller 18 and plunger 19 of control valve 20. Control valve 20, the vertical location of which determines the height to which the explosive material is packed in a cartridge 21, is positioned vertically by adjustment means such as provided by the jack 22. The function of the control valve 20 is further described 25 with reference to the hydraulic and electric systems of Figure 4 in a subsequent paragraph. Resilient pads 23 are located on the frame 10 and tamping cylinder assembly 11 to absorb the shock upon being struck by the control block 17 at the extremes of its travel.

The cartridge 21 to be filled by explosive material is fitted over the outlet of a storage means such as funnel 12 containing the explosive material and held in place by a support means such as a support block 24 which is in turn raised into position by the air cylinder piston rod 25 of air cylinder 26. The movement of the air cylinder piston rod 25 is regulated by the control of air to the inlet and outlet connections 27 by means 40 of a four-way valve 28 shown in Figure 4. The funnel 12 is supported by a cross member of frame 10, said cross member being in hinged attachment to frame 10 to facilitate removal of funnel 12 when necessary to be substituted by one whose 45 outlet is of a size to accommodate another cartridge size.

With reference to Figure 2, a preferable vertical adjustment means of control valve 20 is shown in partial section. The turning of adjustment wheel 29 with its threaded shaft 30 extending in threaded attachment to lift pin 31 will raise or lower control valve 20, through the connecting linkage composed of rod 32 and bracket 55 guide 33.

Guide sleeve 34, attached to guide plate 35, is

suitably attached to lift pin 31. As the turning of adjustment wheel 29 vertically actuates the control valve 20, guide sleeve 34, along with the attached guide plate 35 in guided slidable relationship to the rods 36, acts as a support and as a stop at the limits of travel of lift pin 31. The valve bracket 37 is secured in fixed relationship to bracket guide 33, slidably retained by guide block 38 and guide block cover 39. Control valve 20, of a suitable design known to the art, is attached to valve bracket 37 in such a position as to place the plunger roller 18 of plunger 19 in the path of travel of control block 17 shown in Figure 1. When in contact with the reciprocating control block 17, the plunger roller 18 actuates the attached plunger 19 into the control valve body to a position to prevent ingress of air by way of control valve inlet connection 40 and egress of air from control valve outlet connection 41. When not in contact with control block 17, the plunger roller 18 and plunger 19 are on the extreme outward position to permit both ingress and egress of air in control valve 20. A more complete description of the function of the control valve in the regulatory system of this invention will be subsequently disclosed.

With reference to Figure 3, the tamping cylinder assembly 11 is composed of piston 42 with cup packing 43 held in clamped attachment thereto by clamping means provided by packing retainers 44 held in the position shown by threaded relationship with retainer stud 45. Piston rod 14, rigidly secured by suitable means to the packing retainers 44, extends from both sides of piston 42 and being of smaller diameter than the inside diameter of cylinder 46, an upper fluid pressure chamber 47 and a lower fluid pressure chamber 48 are formed on the upper and lower side respectively of the piston 42. Cylinder heads 49 are attached to both ends of cylinder 46 with adjustably attached packing gland nut 50 holding packing 51 tightly in a cavity formed between cylinder head 49 and piston rod 14 in order to effectively prevent the escape of fluid from chambers 48 and 47.

Figure 4 is a schematic diagram showing the hydraulic system for operating the upward and downward strokes of the tamp rod, the air system for operating the air cylinder, and the electrical control system for securing automatic or manual operation of the invention.

In the example illustrated the source of power is an electric motor 52, supplied with electrical energy from a current source 53 through starter box 54. The starter box 54 in turn is controlled by a time relay 55 actuated by the time pressure switch 56 or by manual operation of the pushbutton station 57. The time pressure switch 56 is intermittently supplied with a charge of air under pressure by the cam operated valve 58 which is actuated by a lobe on cam 59. The valve 58 is supplied with air under pressure through intake 60.

The cam 59 is turned by an extension of the pump shaft 61 and positioned so that a charge of air will be supplied to time pressure switch 56 when the end of the downward stroke of tamp rod 13 has been reached by a lobe of cam 59 actuating a plunger of valve 58 inwardly to a position to allow air from intake 60 to be admitted to time pressure switch 56. With the plunger roller 18 and plunger 19 of control valve 20 in an inward position when in contact with control block 17 and preventing the egress of air from control valve outlet connection 41, the pressure

is maintained in the time pressure switch 56. If the plunger 19 is allowed to maintain this position for a longer interval than that for which the time pressure switch 56 is set, the time pressure switch will actuate the time relay 55 at the moment permitted by entry of pressurized air from valve 58, in turn activating the starter box 54 to stop the motor 52. This will stop the pumping action of reciprocating pump 62, thus no reciprocating fluid pressure will be supplied to the tamping cylinder assembly 11 through adjustable pressure connection 16, by downward pressure cylinder 63 of pump 62 or to the upward pressure connection 15 by an upward pressure cylinder 64 and the end of the tamp rod 13 will be locked in a position within the neck of the funnel 12 when the cartridge 21 is full. In the cycle of operations, pressure supplied by the downward pressure cylinder 63 will force the piston 42 downward and at the same time aid in forcing the return of fluid through the upward pressure connection 15 to the upward pressure cylinder 64 and vice versa.

The pushbutton station 57 connected to the starter box 54 is used at the discretion of the operator to stop or start the movement of the tamping rod 13. Movement of the tamping rod 13 can be made "automatic" as subsequently described or "manual" which involves the operator's manipulation of the pushbutton station 57 by the proper setting of the automatic-manual selector station 65. The manual setting is used when the operator desires to raise the tamp rod to its uppermost position after the tamp rod has been automatically stopped with the end of the tamp rod 11 within the neck of the funnel 12.

The pressure cylinders 63 and 64 of the reciprocating pump 62 each displace in one stroke of piston 66 or 67 of said respective cylinders the volume of fluid necessary to actuate the tamping rod in a given direction to its extreme position. As the cartridge 21 becomes filled with dynamite from the funnel 12 the downward stroke of the tamp rod necessarily becomes shorter and the excess fluid pumped is relieved through pressure relief valve 68 set at a desirable relieving pressure commensurate with the density of pack required. The by-passed fluid from the pressure relief valve 68 flows into a fluid tank 69.

The upward stroke of the tamp rod is performed by fluid forced into the tamping cylinder assembly by the piston 67 and the excess fluid pumped is relieved through pressure relief valve 70. The by-passed fluid from the pressure relief valve 70 flows into the fluid tank 69. It should be noted that in the preferred pumping arrangement shown, the pistons 66 and 67 are connected to a common arm of crank shaft 61 whereby on an outward pressure exhaust stroke of piston 66 an opposite intake stroke of piston 67 takes place and vice versa. A supply line to each pressure cylinder from the tank 69, with a suitable loaded check valve 71 therein to prevent discharge back into the tank on a compression stroke, serves to supply makeup fluid to the system to replenish that which may be lost.

The air supply 72 is connected to the four-way valve 28 which is manually controlled at the discretion of the operator to provide either upward or downward movement to the air cylinder piston rod 25 by way of inlet and outlet connections 27 of air cylinder 26.

The automatic operation of the invention is as follows, referring to Figure 4: the funnel 12 is kept supplied with explosive material to be

tamped or packed into the cartridge 21. The selector station 65 should be set for "automatic" operation. By pressing the "start" button of pushbutton station 57 the tamping rod 13 is given the desired vertical reciprocating motion and pushes before it explosive material from the funnel 12 into the cartridge 21. With each stroke of the tamping rod 13 the level of the packed explosive material in cartridge 21 rises and it is evident that as the strokes become shorter a longer pause will take place at the end of each stroke during which interval the excess fluid pumped by the cylinders 63 and 64 will be discharged through the respective relief valves 68 and 70 into tank 69.

At the discretion of the operator a loosely or tightly packed cartridge can be produced merely varying the pressure at which the relief valve 68 is set to relieve the actuating pressure to adjustable pressure connection 16.

When the cartridge 21 is filled to the desired depth and the control valve 20 located in the proper position in the vertical path of control block 17, to maintain the plunger roller 18 and plunger 19 in contact with the control block 17 at the end of its downward stroke and in an inward pressure holding position for a sufficient interval to actuate the time pressure switch 86, the time relay 55 and starter box 54 are actuated to stop the electric motor 52 and reciprocating pump 62 supplying the tamping actuating medium. Termination of the tamping operation is thus accomplished with the end of the tamp rod within the neck of the funnel 12. The control valve 20 is raised or lowered to the desired location by manipulation of adjustment wheel 29. The time during which pressure must be maintained before the circuit is closed in the time pressure switch 86 is adjustable and details of construction and operation of a switch of this type is well known to those versed in the art.

With the cartridge 21 filled to the desired depth and the tamp rod automatically held inoperative by the termination of movement of the fluid in the system, the operator may turn the control handle of the four-way valve 28 to direct the air supply to cylinder 26 so that the air cylinder piston rod 25 will be forced downward carrying with it the support block 24. The loaded cartridge 21 may be taken out of the machine and an empty cartridge 21 placed on the support block 24 ready to be raised into position under the funnel by manipulation of the four-way valve 28. In order to start the tamping operation the "start" button of pushbutton station 57 is pressed and the operation described above is repeated.

If manual operation is desired the automatic-manual switch 65 is set at "manual" and the tamping operation can then be started or stopped at the will of the operator by using the pushbutton station 57.

In the alternative embodiment of the invention shown in Figure 5, the frame 10 has been elongated to receive a plurality of vertically disposed and horizontally spaced tamping cylinder assemblies 11, funnels 12, air cylinders 26, related control mechanism and so forth described hereinabove with reference to the preferred embodiment.

The elongated valve bracket 78 extends across the front of the invention and is supported at each end by a bracket guide 33 of the adjustment control shown in and described with reference to Figures 1 and 2 of the preferred embodiment of the invention. A control valve 20 is attached to

the elongated valve bracket 78 in juxtaposition to each tamping unit and positioned with respect to the control block 17 as hereinabove described. Each tamping unit is operated and individually controlled in the manner shown and described hereinabove and particularly with respect to Figure 4.

The operation of the invention has been found to be extremely satisfactory, consistent density and uniformity of tamped dynamite cartridges having been obtained at a high productive capacity. An outstanding feature of this device is the high degree of safety with which it can be operated and controlled over a wide range of tamping pressures imposed upon the dynamite in the tamping operation.

What I claim and desire to protect by Letters Patent is:

1. In a machine for tamping dynamite into cartridges, the combination with a frame of a tamping means including a tamp rod and a double-acting hydraulic cylinder assembly; means for hydraulically actuating said tamping means including a hydraulic fluid reservoir, a hydraulic fluid pump connected by supply lines to said cylinder assembly with opposed cylinders having pistons therein connected to a common crank arm operable to alternately supply fluid to and exhaust fluid from each end of said cylinder assembly, adjustable relief valves adapted to relieve the pressure in said supply lines into said reservoir at a predetermined pressure, a makeup supply from said reservoir to each pump cylinder, and a rotative motive power for said pump; control means for said hydraulic actuating means; a storage member for said dynamite in coaxial alignment with said tamp rod and adapted to retain the material to be tamped; a cartridge support assembly; and means of supply and control of a pressured fluid to said support assembly.
2. In a machine for tamping dynamite into cartridges, the combination with a frame of a tamping means including a tamp rod and a double-acting hydraulic cylinder assembly; means for hydraulically actuating said tamping means; control means for said hydraulic actuating means including a control valve disposed in the path of and responsive to contact with said tamping means, vertical adjustment means for said control valve, and means responsive to said control valve adapted to stop the tamping of said cartridge when a predetermined level has been reached in filling said cartridge; a storage member for said dynamite in coaxial alignment with said tamp rod and adapted to retain the material to be tamped; a reciprocable cartridge support assembly; and means of supply and control of a pressured fluid to said support assembly.
3. In a machine for tamping dynamite into cartridges, the combination with a frame of a tamping means including a tamp rod and double-acting hydraulic cylinder assembly; means for hydraulically actuating said tamping means; control means for said hydraulic actuating means including a control valve disposed in the path of and responsive to contact with said tamping means, vertical adjustment means for said control valve, a means responsive to said control valve adapted to stop the tamping of said cartridge when a predetermined level has been reached in filling said cartridge; a storage member for said dynamite in coaxial alignment with said tamp rod having an outlet adapted to retain one end of said cartridge in coaxial alignment with said tamp rod; a cartridge support assembly; and

means of supply and control of a pressured fluid to said support assembly.

4. A machine for tamping dynamite into cartridges having in combination a support frame; at least one tamping assembly including a reciprocable tamp rod and a double-acting hydraulic cylinder assembly; means for supplying pressurized hydraulic fluid to the tamping assembly; means for controlling the flow of the pressurized hydraulic fluid which include a control valve assembly disposed in the path of a reciprocable portion of the tamping assembly and which is mechanically actuated thereby; a stationary storage means for dynamite for the tamping assembly disposed in coaxial alinement with the tamp rod and having an orifice in the bottom thereof through which the tamp rod and dynamite may pass; and a cartridge support assembly.

5. A machine for tamping dynamite into cartridges having in combination a support frame; at least one tamping assembly including a reciprocable tamp rod and a double-acting hydraulic cylinder assembly; means for supplying pressurized hydraulic fluid to the tamping assembly; means for controlling the flow of the pressurized hydraulic fluid which include a control valve assembly disposed in the path of a reciprocable portion of the tamping assembly and which is mechanically actuated thereby; a stationary storage means for dynamite for the tamping assembly disposed in coaxial alinement with the tamp rod and having an orifice in the bottom thereof through which the tamp rod and dynamite may pass; a reciprocable cartridge support assembly; and means of supply and control of a pressurized fluid to said support assembly.

6. A machine in accordance with claim 5 in which the tamping assembly comprises a double-acting hydraulic cylinder, a piston disposed therein, a piston rod extending from upper and lower surfaces of the piston, and a tamp rod secured to the lower end of the piston rod.

7. A machine in accordance with claim 5 in which the means for supplying pressurized hydraulic fluid to the tamping assembly comprises a reservoir for hydraulic fluid; a pump for hydraulic fluid connected by supply lines to the

opposite ends of the tamping assembly cylinder, said pump having opposed cylinders, each of which contains a piston connected to a common crank arm and being operable to alternately supply hydraulic fluid to and exhaust hydraulic fluid from each end of the tamping assembly cylinder; adjustable relief valves disposed in each of said supply lines and in communication with the reservoir; a make-up supply from said reservoir to each pump cylinder; and rotative power means for said pump.

8. A machine in accordance with claim 5 in which the control means has in combination a valve assembly mounted in a vertically adjustable position adjacent the tamping assembly and comprises a body equipped with a passageway for fluid medium; a chamber disposed in the body which intersects the passageway; a plunger, one end of which is slidably disposed in the chamber and restrained by resilient means for closing the passageway; and a roller mounted on the end of the plunger and disposed in the path of a reciprocable portion of the tamping assembly; one end of said passageway being connected to a source of pressurized fluid medium and the other end being in communication with a time-pressure switch which interrupts the flow of hydraulic fluid to the tamping assembly when the reciprocable tamping assembly member contacting the roller causes the plunger to interrupt the flow of fluid medium to said switch for a predetermined period of time.

Certificate of Correction

Patent No. 2,515,323

JOSEPH STUART, II

July 18, 1950

It is hereby certified that error appears in the printed specification of the above numbered patent requiring correction as follows:

Column 5, line 28, for "switch 86" read switch 56; column 8, line 20, for the word "for" read *from*;

and that the said Letters Patent should be read as corrected above, so that the same may conform to the record of the case in the Patent Office.

Signed and sealed this 17th day of October, A. D. 1950.
